UNITED STATES PATENT OFFICE

145,658

DESIGN FOR AN OVERHEAD MONORAIL TRAIN

Clinton B. Clark, Oak Park, Ill.

Application October 15, 1945, Serial No. 122,843

Term of patent 14 years

(Cl. D66—1)

To all whom it may concern:

Be it known that I, Clinton B. Clark, a citizen of the United States of America, residing at Oak Park, in the county of Cook and State of Illinois, have invented a new, original, and ornamental Design for an Overhead Monorail Train, of which the following is a specification, reference being had to the accompanying drawings, forming part thereof.

Referring to the drawings, Fig. 1 is a side elevational view of an overhead monorail train, em-

bodying my new design; Fig. 2 is a top plan view; Fig. 3 a bottom plan view; Fig. 4 a front elevational view; Fig. 5 a rear elevational view; and Fig. 6 is a top perspective view of the same.

The dotted line showing in the figures of the drawing is for illustrative purposes only.

I claim:

The ornamental design for an overhead monorail train, substantially as shown and described.

CLINTON B. CLARK.
